UNITED STATES PATENT OFFICE.

CLIFTON W. NIXON, OF NEW YORK, N. Y.

COIN-CONTROLLED VENDING AND CHANGE-MAKING MACHINE.

Application filed July 27, 1922. Serial No. 577,822.

My invention relates to a coin-controlled vending and change-making machine, designed to contain a plurality of stacks or groups of articles of different kinds or of the same kinds and to vend the different stacks or groups of articles at different prices or at the same prices, accordingly as the machine is set, the machine automatically retaining the price of the article sold and automatically returning to the purchaser along with the article sold the amount of the change, if any, due him, the amount of the change returned representing the difference between the size or denomination of the coin deposited and the price of the article sold.

The particular machine illustrated and described in this application has been designed in particular for vending different packages or brands of cigarettes and for returning the correct change where change is due the purchaser, in exchange for the deposit of a half-dollar, or of a quarter, or of two dimes; and I desire to make it understood that in thus illustrating a particular embodiment of my invention designed for the particular purpose indicated, I have not intended to limit the broader aspects of the invention to a machine adapted for that particular purpose only. The machine involves principles of general application which may be variously adapted and modified for vending articles of different kinds at different prices, not only of cigarettes, but also of other articles of various forms, packaged or otherwise, and therefore it is my intention to cover in some of the broader claims hereunto appended, these principles in any modifications of construction and design in which they may be embodied, as well as to cover the specific adaptation of such principles here illustrated for the particular purpose above indicated.

More specifically considered, the machine of the present invention contemplates the provision of a coin receiving chute for each size or denomination of coin that may be used to effect the operation of the machine and the consequent delivery of the merchandise with the customers change. It further contemplates for each coin chute, the provision of two aligned longitudinally movable coin-controlling levers co-operatively headed to receive between them the deposited coin as it falls from its chute, such deposited coin forming a connection between

said levers so that the second lever and consequently the machine may be operated by the first lever. The actuation in this manner of each second lever controls the operation of a master-pusher which effects the delivery of the article purchased along with the change, if any, to the purchaser. Provision is also made for positively ejecting the deposited coin from between the co-operatively headed coin-controlling levers at a predetermined place during their operation.

Another object of my invention is to provide a rotary magazine constructed with a plurality of stack groups comprising a merchandise-stack and a set of associated coin-stacks, with each of which is associated an ejector adapted to be actuated by the master-pushers under various combinations and conditions.

Another object of my invention is to provide means for manually turning or stepping around the rotary magazine so as to bring any desired stack group in proper register with that particular master-pusher which corresponds with the size or denomination of the coin deposited, and further to provide means for normally holding the rotary magazine locked in stationary position and for automatically unlocking the same when it is to be rotated.

Another object of my invention is the provision of mechanism, automatically controlled, for preventing the deposit of coins when a stack of any group has been exhausted of its contents, and also to accomplish this object without interfering in any way with the usual deposit of coins controlling delivery from the groups of stacks which have not been exhausted of their contents.

Portions of the subject matter of the present invention are also described in and certain novel features of the invention herein described, but not herein claimed, are claimed in my two companion applications for patents, both filed on June 5, 1924, and bearing Serial No. 718,162, and Serial No. 718,163, respectively. Both of these companion applications are divisions of the present application.

The nature of the general principles and objects above referred to, as well as other and additional objects and advantages which will become apparent as the description proceeds, and the manner in which they are em-

bodied in concrete form and means are explained in the following detailed description of the particular mechanisms herein illustrated, to which reference is now directed.

In the drawings which form part of this application:

Figure 1 is a vertical cross-section of my machine, showing the internal mechanisms including the mechanism for locking and the mechanism for manually actuating the rotary magazine, and a unit of the mechanism for causing the ejection of merchandise and change from a stack group of the rotary magazine, here shown, in order to avoid confusion of lines, with only a partial number of the stack groups.

Fig. 2 shows a top plan view of the machine with the top or cover removed.

Fig. 3 is a transverse sectional view, taken on the line 3—3 of Fig. 1, looking in the direction of the arrows, this view showing in particular the arrangement in the rotary magazine of the stack groups and also the arrangement of the master-pushers.

Fig. 4 is a partial section of a merchandise stack, showing the construction of the ejector mechanism and also some of the parts employed for effecting the closing of the coin-deposit slot gate.

Fig. 5 is a front elevation showing some of the parts as are shown in Fig. 4, the weighted plunger here being shown in position to hold closed the coin-deposit slot gate.

Fig. 6 is a partial sectional view of a coin-stack with the ejector mechanism associated therewith.

Fig. 7 is a partial sectional view from the rear, showing the gate for closing the coin-deposit slot and also the by-pass for spurious deposits.

Fig. 8 is a view in perspective showing the construction of the co-operatively headed coin-controlling levers for sustaining a coin and the means connected therewith for effecting the discharge of the sustained coin during the actuation of the levers.

Fig. 9 is a fragmentary view in perspective showing a stack unit or group consisting of a merchandise-stack and a set of coin-stacks.

Fig. 10 is an enlarged fragmentary face view of a merchandise-stack, illustrating in particular the liner which may be employed to reduce the interior dimensions.

Fig. 11 is a detail perspective view of an ejector, showing the auxiliary ejectors that may be connected thereto.

Figs. 12 and 13 are progressive details showing a modified form of co-operative heads on the coin-controlling levers.

Fig. 14 is an exterior view of a casing or cabinet for the machine.

Fig. 15 is a partial sectional view of a merchandise stack and of a master-pusher,

illustrating in particular the means employed for preventing the operation of the ejector for one of the merchandise stacks.

The same reference characters indicate the same parts in all the figures.

The machine in the present embodiment contemplates the provision of a casing of suitable form, illustrated by way of example in Figs. 1, 2, 3 and 14, the same being preferably constructed of sheet metal and having an outwardly curved front or face panel 20, opposed side plates 21 and 22, rear plate 23, bottom plate 24 and a hingedly engaged top plate 25. For the purpose of reinforcing the casing, there is preferably provided at each inner corner thereof an upright angle-iron 26 as shown. Such corner angle-irons may, if desired, be rigidly connected by cross-pieces (not shown) or such other skeleton frame connections as may be conducive to the strength and rigidity of the structure. A short distance above the bottom plate 24, I preferably provide a horizontal partition or platform 27, and between said bottom plate 24 and said partition 27 there is slidably mounted a money drawer 28 which opens at the front of the casing.

In carrying out my invention, I provide, above the horizontal partition 27, a rotary magazine in the form of a vertical cylindrical structure, shown in the present exemplification as made up of eight stack groups represented generally by the reference characters A, B, C, D, E, F, G and H. Each of these stack groups includes a merchandise-stack 29 and a set of coin-stacks 30, 31 and 32. The merchandise-stacks, intended in the present embodiment as receptacles for holding columns of packages of cigarettes, are of rectangular form in cross-section; while the coin-stacks are, of course, of circular form in cross-section and differ in size or diameter as may be necessary in order to accommodate the different sizes of coins for which they are intended, for instance, in the present embodiment, 30 denotes the stacks for holding quarters, 31 the stacks for pennies and 32 the stacks for nickels.

The rotary magazine is very simple in construction, comprising a top ring plate 33 and a bottom ring plate 34, rigidly connected by the vertically extending merchandise-stacks 29 which are arranged as best shown in Fig. 3, in equi-spaced positions and radially with respect to the center about which the ring plates rotate. The actual rigid connection of the merchandise-stacks with the ring plates may be effected in any suitable or appropriate manner. As herein shown, the upper ends of the merchandise-stacks are projected through suitable openings or apertures 33' provided in the top ring plate 33 (Fig. 1), bent over thereupon as at 35 (Figs. 1 and 2) and made rigid by brazing or other suitable means. At their lower ends, the

merchandise-stacks are made with oppositely projecting ears 36 (Fig. 9) whereby to be removably secured upon the bottom ring plate 34 by means of screws 37 or otherwise; 5 and it will be observed that these connections are so made that the merchandise-discharge openings 38, with which the faces of the merchandise-stacks are provided, come even with or in close proximity to the outer 10 peripheral edge 40 of the ring plate 34, in order that a rectangular package of cigarettes as represented at 41 may be readily kicked out or discharged bodily sidewise from the stack and clear of the ring plate. 15 The coin-stacks are arranged in a circle upon the bottom plate 34, intermediate or approximately intermediate the widths of the merchandise-stacks, the stacks making up each group being closely associated in a 20 systematic order and the stack groups being equi-spaced apart, all as clearly shown in Fig. 3. The largest coin-stacks shown in the present exemplification are the quarter stacks 30, and as these require the most space 25 they are preferably placed individually at the ends of the merchandise-stacks, while the penny stacks 31 and the nickel stacks 32 are located together at the opposite ends thereof. In relation to the direction of movement of the magazine, which is from right to left, the order of the stacks comprising each group is quarter stack 30, merchandise-stack 29, penny stack 31 and nickel stack 32. The merchandise-stacks in respect of their 30 cross-sectional dimensions have their greater lengths in the general direction of the circle of stack groups so that rectangular-shaped packages of cigarettes as 41 (Fig. 9) can be ejected through the opening 38 and out 35 over the outer edge 40 of the ring plate 34 with a minimum stroke on the part of the ejectors, presently to be described.

The coin-stacks 30, 31 and 32 are each formed at their lower ends with oppositely 40 directed ears 42 for securement to the ring plate 34 by means of screws 43 or other equivalent means. Said coin-stacks are each provided with a coin discharging opening 44, immediately before which for each stack 45 30, the ring plate 34 has a peripheral opening 45, and for each of the stacks 31 and 32, a common peripheral opening 46. The purpose of the openings 45 and 46 is to permit the coins as they are ejected or discharged 50 from the openings 44 to fall onto the delivery slideway 47 which inclines downwardly and outwardly of the casing passing through and forming the bottom for the delivery opening or slot 48 in the front panel 20 and 55 terminating in an upstanding inwardly curved portion 49 to provide a delivery pocket 49'. Inasmuch as the coins or even several coins stacked together are of considerable less thickness than a package of 60 cigarettes, the coin-stacks in the present embodiment of the invention, are preferably of less height than the merchandise-stacks and terminate a distance below the top ring plate 33, as shown. The cost of unnecessary material and the burden of unnecessary weight 70 are thus avoided.

The ring plate 34 centrally and substantially rearwardly of the location of each merchandise-stack is formed with a downwardly offset or struck out portion 50 which 75 extends radially to and is open at the inner edge 51 of said ring plate. Slidable upon this ring plate in a pair of confronting guides 52 secured thereupon along the slot edges 53 resulting from the provision of the struck out portion 50, is a merchandise ejector 54 of which there is one thus provided for each merchandise-stack. Each ejector (Fig. 4) is formed at one end with an upstanding pusher lug 55, which slidably 80 fits in an opening 56 in the merchandise-stack, at the other end with an upstanding movement receiving lug 57 of a length adapted to slidably come between the guides 52, and on its underside forwardly of the position of said last lug with a depending lug 58 slidably fitting between the slot edges 53. 59 is a push spring confined in horizontal position between the depending lug 58 and the portion 50 at the point 60, this spring normally urging the ejector into thrust position with the depending lug in engagement with stop 61 secured at 62 to the portion 50, and with the pusher lug 55 clearing the interior of the merchandise-stack in position to engage and eject a package of cigarettes lying therewithin upon the ring plate 34. 95

For each of the coin-stacks, there is similarly provided a downwardly offset or struck out portion 64, a spring-pressed ejector 65 operatively held in guides 66, and an ejector stop 67, these parts in their arrangement and in their details being in all respects similar to the corresponding parts for the merchandise-stacks, except that they are of smaller dimensions, and it will be understood in this connection that these parts as regards the coin-stacks 30, 31 and 32 and as regards the merchandise-stacks 29 as well, 100 may vary in dimension and also in specific form to the extent necessary to meet the conditions by way of different sizes in the denominations of coins and different sizes and forms of the packages. In the present embodiment, as will be observed from an inspection of Fig. 3, the ejectors 54 extend beyond the inner edge 51 of the bottom ring plate while the ejectors 65 terminate short of said edge for the reason that the packages of cigarettes being of larger cross-dimensions than the diameters of the coins, require a more extensive thrust movement for their ejection. Similarly the actual dimensions 110 of the ejectors 65 for the coin-stacks 30, 31 120 and 32 are considerably less than the dimensions of the merchandise-stacks 29. 125

130

and 32 may vary as may be necessary to effectually eject the coins therein contained.

As a means of supporting the magazine for rotary movement, I pass around and secure to the merchandise-stacks 29, below the top ends thereof, a ring 68, from which projects at equi-spaced distances the spindles 69 carrying rollers 70 adapted to travel in a grooved ring track 71, supported upon brackets 72 which are secured to the casing plates or any suitable framework connected therewith. A distance above its bottom end the magazine is guided or braced in operative position by means consisting of a U-shaped ring 73 which is passed around and secured to the merchandise-stacks 29, and in which at equal distances are secured verticle spindles 74 carrying rollers 75 adapted to turn on a guide ring 76, supported on brackets 77 which may be secured to the casing frame plates or to any suitable reinforcing framework that may be employed in connection therewith.

The top ring plate 33, around its inner circumference, is formed with equi-spaced upstanding teeth 78 of which in the present embodiment there are eight in correspondence with the number of stack groups. Around its outer circumference said ring plate is formed with an upstanding flange 79 of considerably greater height than the teeth 78. This flange is provided near its top edge with eight equi-spaced keeper-openings 80, there being one keeper-opening for each stack group. 81 designates a horizontal spider-frame, herein shown as formed with six (Fig. 2) radially extending arms of which 82, 83 and 84 have downturned ends as shown at 85 (Fig. 1) whereby to be secured by screws 86 or equivalent means to the casing plates or any reinforcing skeleton frame parts that may be employed. Spider-frame arms 87, 88 and 89 project towards the front panel 20 in equi-angular relation and have their ends attached to the inclined slideway 90. Engaged on a pivot stud 91 which depends from the spider-frame, approximately centrally thereof, is a draw-bar 92 having a hingedly engaged finger 93 adapted to engage the teeth 78 successively and turn the magazine step by step, said finger being normally held pressed downwardly in position to engage said teeth by the flat spring 94 bearing thereon and attached to the draw-bar at 95, the said spring 94 yielding in an obvious manner to permit the finger to slide over the points of the teeth.

Located in position to be engaged by the finger 93 each time it slides over the point of a tooth 78 is a downwardly inclined contact plate 96 which is pivotally held in a hanger 97 depending from the spider-frame. 98 designates the magazine locking bar, slidably fitted in an opening 99 provided in the

lug 100 which depends from the offset portion 101' formed on the spider-frame arm 82. Said locking bar has its inner end pivoted to the upper end of the contact plate 96 and is normally urged into position to have its outer end engaged with a keeper-opening as 80 by a pull spring 102, here shown as connecting the locking bar with the lug 100.

As clearly shown in Figs. 1 and 2, the draw-bar 92 is normally urged in a direction to draw or step the magazine from right to left by a pull spring 103 which connects it with a depending lug 104 on a web 105 comprising a connection between the spider-frame arms 88 and 89. 106 is a horizontal push rod slidably journaled at 107 in the lug 104 and at 108 in the casing front panel 20 in position to engage and move the draw-bar from one tooth to another, its inward thrust movement being limited by the base 109 of the exterior push button 110 and its outer movement by the engagement of a pin 111 with the lug 104. It will be understood that the magazine is normally held locked in stationary position by the projection of the locking bar 98 into one of the keeper-openings 80, and that such position of the locking bar maintains the contact plate 96 in position to be engaged by the finger 93 as it clears the high point of a tooth 78. In operation the button 110 is given an inward thrust by the thumb or finger to move the draw-bar finger 93 over the high point of the next succeeding tooth and to withdraw the locking bar from its keeper; whereupon, upon removing the thumb or finger from the button, the draw-bar finger under the influence of spring 103 will draw the magazine until the locking bar slips into the next succeeding keeper-opening. Every thrust thus made on the button will step the magazine one-eighth of a revolution.

I now come to the means and mechanism for receiving and sustaining the deposited coins through the agency of which additional mechanism including master-pushers are controlled for effecting the operation in various combinations of the ejectors associated with the several stack groups. In the present disclosure, three sets or units of such mechanisms are provided, one set or unit for each size or denomination of coins that may be deposited in the machine, namely, half-dollars, quarters and dimes. For the half-dollar coins, I provide a pair of controlling levers 112 and 113; for the quarter coins, the controlling levers 114 and 115; and for the dime coins, the controlling levers 116 and 117. The members of each pair of levers are arranged in horizontal longitudinal alinement in spaced-apart positions. With respect to each other, the pairs of levers are radially disposed, the pair 112 113 being alined above the position of the spider-

frame arm 87, the pair 114 115 above the arm 88, and the pair 116 117 above the arm 89, as best illustrated in Fig. 2. Exterioly of the front panel 20, the members 112, 114 and 116 are equipped with buttons 118, 119 and 120, respectively; and thereabove (Fig. 14) said front panel is provided with the coin-deposit slots 121, 122 and 123 for the half-dollars, quarters and dimes, respectively. On the interior of the casing, in communication with the coin-deposit slots 121, 122 and 123, are the respective coin chutes 124, 125 and 126, which lead downwardly and inwardly to deliver their coins to the proper pairs of levers, said coin chutes being each of the proper interior dimensions to permit its coins to roll inwardly upon their circumferences, and each having a downturned end as 127 from which the coins will fall substantially vertically.

The several pairs of coin-controlling levers being supported by like parts and their operation being similarly regulated, a description in detail of these matters relative to one pair will suffice for all. To this end, by way of example I will refer to the pair coin-controlling levers 114 115, whose supporting and regulating parts are illustrated in detail in Figs. 1 and 8. These levers are preferably made in the form of straight bars of rectangular shape (in cross-section), the inner lever 115 being much the longer. The outer lever 114 is supported for longitudinal movement at 128 in the U-shaped bracket 129 and at 130 in the front panel 20, said bracket being rigidly secured to the inner face of said front panel. At its inner end the lever 114 is formed or otherwise provided with a vertically extended head 131, in which is cut a vertical groove 132 open and laterally widened or flared at the top as shown at 133. Coiled around this lever is a push spring 134, one end whereof is secured thereto at 135 and the other end to the bracket at 136, the purpose of the spring being obviously to urge the lever into its outer or thrust position, such outward urge being limited by said pin 135 which acts as a stop.

The inner lever 115 is journaled for reciprocating movement in the bearings 136 and 137 provided in the uprights or standards 138 and 139 respectively which rise from the spider-frame arm 88 to which they are made fast. Upright 139 is made with an arm 140 projecting closely over the top of the lever 115 and having an upturned end 141, designed to serve as a trip as will presently appear. Upright 138 is made with a vertical extension 142 and a lateral extension 143, the latter being parallel with lever 115. To the vertical extension 142 is pivoted at 144 a kick-out bar 145 having a slot 146 upwardly inclined at 147 and having in addition thereto a downturned forward end 148. To the lateral extension is pivoted at 149

a bell crank lever 150 whose vertical arm is slotted at 151 to receive a pin 152 projecting from the lever 115. 153 is a pull spring which connects the bell crank lever with the upright 138 so as to constantly urge the lever 115 into its forward or thrust position, the urge of the spring being limited by the engagement of a guide-piece 154 with the upright 139, said guide-piece having its upper end bent over at 155 and entered in the slot 146 whereby to actuate the kick-out bar 145 when the lever 115 is thrust inwardly.

At its forward end the lever 115 is made with a side extension 156 to which is pivoted at 157 a head 158, grooved vertically at 159 and flared at 160 in correspondence with the head 131. A spring 161 pinned at 162 to the lever 115 and bearing on the under side of the head 158 normally urges said head upwardly in proper alignment with the head 131, the upward movement of head 158 being properly limited by the engagement of a shoulder 161' with the extension 156. Said pivoted head 158 has a rounded or cam-like portion 162' so that it may swing downwardly whenever a shoulder 163 formed on its top side engages the trip or lug 141 during the inward thrust of the lever 115. The heads 131 and 158 are held in such spaced relation by the parts above-described that when a coin, in the present instance a quarter, drops from the deposit chute 125, it will enter the grooves 132 and 159 and be sustained by the co-operating heads. When, in operation, the lever 114 is thrust inwardly, the movement thereof through the medium of the sustained coin is transmitted to the lever 115. When a thrust is made upon the button 119, the coin-controlling levers with the sustained coin between them move together until near the limit of the thrust the trip 141 engages the head 158 and swings it downwardly to effect the discharge of the coin. Simultaneously with the down swing of the pivoted head, the guide-piece 154 enters the slot inclination 147 by which the kick-out bar is given a sudden downward thrust engaging the end 148 thereof with the rim of the coin and thereby positively insuring the discharge of the coin, which falls into the branch chute 164 and thence into the main chute 165 for deposit in the money drawer 28.

The pair of coin-controlling levers 112 113 carry heads 166 167 (Fig. 2) respectively. These heads are similar to those carried by the coin-controlling levers 114 115, except that they are larger and are held spaced-apart the distance necessary to enable them to receive and sustain a half-dollar coin, which is entered through the coin-deposit slot 121 for delivery to said heads 166 167 by the coin chute 124. On thrusting the button 118, the levers 112 113 with the sustained half-dollar move inwardly to

gether until the head 167 is tripped and the coin kicked-out as in the previous instance. The half-dollar coin falls into branch chute 168 and thence into main chute 165 for deposit in the cash drawer.

The third pair of coin-controlling levers 116 117 is provided with the heads 169, 170 respectively, these heads being designed to receive, sustain and permit the delivery 10 of two coins (in the present disclosure (of two dimes), the arrangement being such that the lever 117 cannot be actuated by the lever 116 until the second coin has been deposited. The details of this construction are 15 best shown in Figs. 12 and 13, wherein it will be seen that the head 169 is made integral with its lever and has a vertical slot 171 open at the top, and that the head 170 is pivotally engaged with its lever, has a co- 20 operating slot 172 and is urged into proper co-operative position by a spring 173, all of which features do not differ in principle from those hereinbefore described. But it will be noted that these heads are elongated 25 considerably in a direction downwardly of the longitudinal centers of the levers 116 117, so as to be capable of sustaining two dimes as 174 175, one upon the periphery of the other, with the lower dime 174 forming 30 a connection below the center line of thrust while the upper dime 175 is supported thereon to form a connection in the center line of thrust. When two dimes have been inserted, the operation is substantially like 35 that hereinbefore described. On thrusting the button 120, the levers 116 117 with the sustained dimes move together, until the head 170 is tripped and the dimes discharged or kicked-out into the branch chute 40 176, passing thence through the main chute 165 to the cash drawer. If only one dime is deposited, a different result will be obtained, since it forms a connection below the line of thrust only, and the movement of the lever 45 116 will swing the head 170 on its pivot and discharge the sustained dime without actuating the lever 117. In this case the discharged dime falls onto the slideway 90 and thence into a channelway 177 for delivery 50 to the slideway 47 and thence to the customer. Under these provisions anyone who forgets to deposit two dimes or who attempts to tamper with the machine, will not be able to operate the machine and will have 55 his deposit returned. The slideway 90, which communicates with the channelway 177, extends alike beneath the co-operating heads of all the pairs of coin-controlling levers, so that if a dime should be dropped 60 into either the quarter or the half-dollar deposit slots, it will be returned to the customer. Similarly, a quarter dropped into the half-dollar deposit slot, or any slugs or disks in imitation of coins, dropped into any 65 of the deposit slots, will be returned without

forming a connection for the operation of the machine, except that the article employed by way of an imitation coin be made so perfect as to be caught and sustained between the co-operatively grooved heads. To 70 prevent delivery to or between the co-operating heads of any metal slugs or disks, I contemplate providing alongside each coin chute 124, 125 and 126 a magnet 178 (see 75 Figs. 2 and 7), adapted to attract such articles and divert the same into a by-pass 178' for delivery to the slideway 90 and thence to the user.

For each of the pairs of coin-controlling levers 112 113, 114 115 and 116 117, I provide a master-pusher 179, 180 and 181, in mutual relation in the order mentioned. Although of different lengths for a reason presently to appear, these master-pushers are curved in substantial agreement with the 80 bottom ring plate 34, and each is removably supported in transverse relation on the outer end of an independent longitudinal plate 182, slidably held in a pair of guide-pieces 183, fastened on a block 184 which is secured 85 upon the horizontal partition 27. As clearly shown in Fig. 3, these three sets of slide plates are arranged radially towards the front panel 20 but within the compass of the magazine and they are spaced on the 90 radial lines of the merchandise-stacks, so that as the magazine is stepped around, the merchandise-stacks will become alined therewith successively; and it will be understood 95 in this connection that the co-operative relation between the three sets and the locking and rotating mechanisms hereinbefore described, is such that when the magazine is locked three merchandise-stacks are always alined with the three sets of slide plates. 100 The elevation of the slide plates is such that when they are thrust outwardly or projected, the master-pushers are first brought into engagement with the lugs 57 of the merchandise ejectors and then with the corresponding 105 lugs of the coin-stacks, the master-pushers and the slide plates moving or coming just above the ejector guides.

The inner levers of the pairs of coin-controlling levers are connected with their corresponding master-pushers by a precisely similar chain of parts, and it is thought that a description of one of these chains of parts will suffice for all. Turning, therefore, to Fig. 1, wherein is illustrated by way 115 of example, the chain of parts connecting the inner lever 115 with the slide plate carrying master-pusher 180, it will be seen that the bell crank lever 150, hereinbefore described as having a pin and slot connection with the inner lever 115, has pivoted to its horizontal arm at 185 a yoked sleeve 186 in which is threadedly engaged the upper end of a long rod 187 which extends downwardly through the magazine and has its lower end 120 125 130

threaded into a similar sleeve 188 pivoted at 189 to the horizontal arm of bell crank lever 190, fulcrumed at 191 to a lug 192, made fast in radial alinement with the block 184 to the horizontal partition 27. Pivotally connected at 193 to the vertical arm of bell crank lever 190 is a link 194 whose opposite end is pivotally engaged at 195 with a lug 196 upstanding from the slide 10 plate carrying the master-pusher 180. As will be understood from an inspection of Figs. 2 and 3, the inner levers 113 and 117 are similarly connected with the slide plates carrying their corresponding master-pushers, 179 and 181, respectively. It will be obvious that the inward thrust movement of the inner levers 113, 115 and 117 will cause their corresponding master-pushers to be thrust outwardly to engage and actuate the ejectors for the merchandise and coin-stacks and thereby effect the delivery of the merchandise and coins, each chain of parts being repositioned after each operation by the spring 153 which connects the bell crank lever 150 with the standard 138. Obviously, additional springs may be added, if found necessary to properly effect the repositioning operations.

As shown in Fig. 14 the casing front panel 20 has a hingedly engaged door 197, in which are provided three windows 198, 199 and 200, spaced so as to come in radial line with the merchandise-stacks and through which portions of the merchandise stacks may be seen. The purpose of these windows is to enable the customer to observe the kind or brand of cigarettes carried in each merchandise-stack as well as the price thereof, and to this end each merchandise stack, in a position to be displayed through said windows, should contain some suitable picture, legend or other characterization (not shown in the drawings) indicative of the brand of cigarettes contained therein together with the amount of the purchase price.

At this point I will give a number of examples of the operation of my machine. Let us assume that a customer has a half-dollar and desires to purchase a package of cigarettes, say of the value of seventeen cents, and let us assume further that the merchandise-stack of group H contains packages of cigarettes of the brand desired, for the price of seventeen cents, also that the coin-stacks 30, 31 and 32 of this group contain quarters, pennies and nickels, respectively. This stack group being illustrated as behind the window 198, which comes below the coin-deposit slot 121 for half-dollars, it is unnecessary in this instance to step the magazine in order to make the purchase. The purchaser deposits his half-dollar and thrusts in button 118 with the result that master-pusher 179, which is

of a length to actuate all the ejectors of a group, effects the delivery of a seventeen cent package of cigarettes from the merchandise-stack, a quarter from stack 30, three pennies from stack 31 and a nickel from stack 32. In this connection it is to be pointed out that the coin-stacks are provided with gauge-clamps (Fig. 9) 201 adjustable thereon to control the number of coins that may be delivered; and that the coin-stack ejectors 65 may be provided with auxiliary ejectors as 202 (Fig. 11) by which to eject a predetermined number of coins, the ejectors being of the same or approximately the same thickness as the coins to be acted on, and it will be understood in this connection that each gauge-clamp must be set in agreement with the number of ejectors employed so that the predetermined number of coins will always be discharged. Thus in order to obtain the delivery of three cents from the penny stack 31 of the stack group H, in the instance above cited, there must have been employed in connection with the penny stack two auxiliary ejectors 202, and the gauge-clamp 201 must have been set in agreement therewith. With the auxiliary ejectors and the gauge-clamp once set in agreement on a coin-stack, the same number of coins will always be ejected from the stack on each outward thrust of the ejector. In the event of any change in price, the owner of the machine may reset these parts as may be necessary to give one coin or the proper predetermined number of coins.

Assume that the purchaser has two dimes and desires to purchase a seventeen cent package from group H. By successive thrusts on button 110, he steps the magazine around until the H group cigarettes are behind window 200. On deposit of the two dimes in slot 123 and on the actuation of button 120, master-pusher 181 of a length to operate the ejectors for the merchandise-stack and the penny stack only, will effect the discharge of a seventeen cent package and three pennies. If this purchaser has a quarter, he steps group H to the window 199, deposits the quarter in slot 122, thrusts button 119 and master-pusher 180, which is not long enough to engage the ejector for the quarter stack, will effect the delivery of a seventeen cent package of cigarettes, three pennies and one nickel.

By way of another example, suppose one customer has two dimes, another customer a quarter and still another a half-dollar, each desiring a package of cigarettes selling at twenty cents and that the stack group A contains the brand desired. Now as the cigarettes sell for twenty cents, no pennies will be placed in penny stack 31 of this group since no pennies in change will be required. On stepping group A to window 200 and depositing his two dimes and thrusting the

button, the first customer will receive a package of cigarettes worth twenty cents and no change, for master-pusher 181 does not engage the ejectors for the quarter and nickel stacks, and the penny stack is empty. Now let the second customer step group A to window 199 and deposit his quarter. A twenty cent package and a nickel will be delivered, as master-pusher 180 will not 10 operate the quarter ejector and the penny stack is empty. Next our third customer moves group A to window 198 and deposits a half-dollar. He will receive a twenty cent package of cigarettes, a quarter and a nickel, 15 since master-pusher 179 is of a length to engage all the ejectors, although the penny stack is empty and nothing is received therefrom. Thus it will be seen that in varying the lengths of the master-pushers different 20 but predetermined results can be obtained from the same group, and also that by varying the number of auxiliary ejectors and the gauge-clamp corresponding thereto or by removing the coins from one of the coin stacks, 25 other different predetermined results can be obtained from the same group. For instance, suppose the stack group B to contain cigarettes selling at sixteen cents, then in such case the penny stack 31 thereof would 30 be set to deliver four pennies. Similarly, if stack group C contained eighteen cent cigarettes, the penny stack thereof would be set to deliver two cents. Similarly, also, if the stack group D contained nineteen cent cigarettes, the penny stack thereof would be set 35 to deliver one cent in change.

Suppose the stack group F to contain cigarettes selling at fifteen cents. In such case it would be necessary in the present embodiment, to substitute a nickel stack as 32 for the penny stack 31. This combination would give at window 200 a package and a nickel, at window 199 a package and two nickels, and at window 198 a package with a 40 quarter and two nickels. Suppose further that the stack group E contains cigarettes for twenty-five cents. In this case provision must be made to prevent any operation taking place at the two dimes window 200. 45 This is accomplished by securing a horizontal stop 203 (see also Fig. 15) at the rear of the merchandise-stack for this group and above its ejector, and also in providing the master-pusher 181 with an upstanding lug 204 to engage said stop and block the 50 operation of the line so that the deposited dimes will be sustained until a group containing cigarettes selling for twenty cents or less has been moved into position to be 55 operated at the two dimes window 200. In other words, in the present embodiment, a package of cigarettes worth twenty-five cents cannot be obtained at the two dimes window, but only at the quarter window and 60 at the half-dollar window. The said stop 65

203 is placed at such elevation that the master-pushers 180 and 179 will come below it when operated and thus function in their usual way. In this instance, no coins would be placed in the penny and nickel stacks of this group, so that at window 199, the package of cigarettes only will be delivered while at window 198 a package of cigarettes and a quarter will be delivered.

In the present disclosure, it is contemplated that a sufficient number of coins will be placed in the coin-stack of a stack group to make the necessary change for all the packages of cigarettes contained in that group, and in the event the contents of a merchandise-stack should become exhausted, provision is made to close each coin deposit slot against the deposit of coins each time the exhausted stack comes into delivery position in connection therewith. As illustrated in Figs. 1, 4 and 5, in each merchandise-stack is provided a weight 205, loosely fitted therewithin and having a centrally depending pin 206 resting on the top of the last cigarette package as 207 (Fig. 4) so that when the latter is discharged, the weight will drop, thrusting the pin through an opening 208 in the bottom ring plate and onto the free end of a treadle 209, pivoted at 210 to a lug 211 secured upon the horizontal partition 27. To the opposite end of this treadle is pivoted at 212 a pull rod 213, which extends upwardly of the casing behind the channelway 177 and through the slideway 90 and has pivotal connection at 214 (for details see Fig. 7) with an angular lever 215 pivoted at 216 to the inner side of the casing front panel. The upper end of this lever has the form of a slot closure gate 217 adapted when the treadle is depressed, to enter a slot 218 provided in the coin-deposit chute 125, immediately behind the coin deposit slot 122. The portion 219 of said lever 215 is made heavy to constitute a weight so that immediately the pin 206 slips off the treadle as the magazine is stepped around, the said lever 215 will swing by gravity withdrawing the gate 217 and opening the coin-deposit slot, and also repositioning the treadle for the next operation.

A similar set of mechanism is provided for each of the other coin-deposit slots 123 and 121. In connection with each of these mechanisms, there is provided upon the horizontal partition 27 a riser 220 terminating (in the direction the magazine turns) in an overhanging ledge 221, under which part of the free end of the treadle comes, so that each time the stock group with the exhausted merchandise-stack approaches delivery position, the pin 206 will engage a riser 220 and rising upwardly thereon, will elevate the weight 205. These rises are so arranged in relation to the locking mecha- 139

nism that just prior to the movement of the exhausted stack into delivery position, the pin 206 will slip off the ledge 221 of the riser and onto the treadle thereby closing 5 the coin-deposit gate. The coin-deposit slots are thus closed for each exhausted stack as it comes into delivery position and automatically opened again for use in connection with the non-exhausted stacks, as the exhausted stack moves out of delivery position.

The merchandise-stacks 29 are preferably made interiorly of a size sufficient to accommodate the largest packages of the more 15 common or popular brands of cigarettes. When smaller packages of cigarettes are to be sold, the interior dimensions of the merchandise-stacks may be reduced to the extent necessary by means of a liner as 222 (Fig. 20 10).

What I claim as new and desire to secure by Letters Patent is:

1. A coin-controlled vending and change-making machine comprising a casing, a 25 magazine inclosed by the casing and provided with a series of groups of stacks capable of holding merchandise and different denominations of coins, a plurality of coin-controlled mechanisms, and means operable 30 by each coin-controlled mechanism for effecting the discharge of merchandise and coins from a different predetermined number of stacks of each group.

2. A coin-controlled vending and change-making machine comprising a casing, a movable magazine inclosed by the casing and constructed with a plurality of merchandise-holding stacks and coin-holding stacks arranged in groups, means arranged within 40 the casing for stepping the magazine, a plurality of coin-controlling mechanisms, and means under the control of each coin-controlling mechanism for effecting the discharge of merchandise and coins from a predetermined number of stacks in each group.

3. A coin-controlled change-making machine comprising a casing, a movable magazine inclosed by the casing normally locked therein and constructed with a plurality of 50 coin-holding stacks arranged in groups, means arranged within the casing for unlocking and stepping the magazine, a plurality of coin-controlling mechanisms, and means under the control of each coin-controlling mechanism for effecting the discharge of coins from a predetermined number of stacks in each group.

4. A coin-controlled vending and change-making machine comprising a casing, a movable magazine therein made up of a plurality of merchandise-stacks and coin-stacks arranged in groups, ejector devices associated with said stacks, means for rotating the magazine, coin-controlling mechanism 60 comprising a pair of reciprocating members

arranged in spaced end to end relation and formed to receive and sustain a coin between them by which to operate the second member from the first member, and means operated by the second member for actuating the 70 ejector devices.

5. A coin-controlled vending and change-making machine comprising a casing, a magazine movably disposed therein and consisting of a plurality of equi-spaced stack 75 groups, structurally independent ejector devices carried by the magazine in association with the individual members of the stack groups, means for rotating the magazine, coin-controlling mechanism comprising a 80 pair of reciprocating members arranged in spaced end to end relation and formed to receive and sustain a coin between them by which to operate the second member from the first member and means under the control of the second member for actuating a 85 predetermined number of ejectors of each stack group.

6. A coin-controlled vending and change-making machine comprising a casing, a 90 magazine movably disposed therein and consisting of a plurality of equi-spaced stack groups, structurally independent ejector devices carried by the magazine in association with individual members of the stack groups, means for rotating the magazine, 95 selective sets of coin-controlling mechanisms comprising a pair of reciprocating members arranged in spaced end to end relation and formed to receive and sustain a coin between them by which to operate the second member from the first member, and independent means under the control of the second member of each set of coin-controlling mechanism for actuating a predetermined number 100 of ejectors in each stack group.

7. A coin-controlled vending and change-making machine comprising a casing, a magazine movably disposed therein and made up of a plurality of merchandise-stacks and coin-stacks arranged in a circle 110 in equi-spaced groups, ejector devices carried by the magazine in association with the merchandise-stacks and coin-stacks and independently operable, means of moving the magazine step by step, selective sets of coin-controlling mechanisms, master-pushers operated by the coin-controlling mechanisms, and contact members fixed on the master-pushers and adapted each to engage and 115 simultaneously actuate a different predetermined number of ejectors in each group.

8. In a coin-controlled vending and change-making machine, a pair of bars 125 mounted to slide in aligned end to end relation from one position to another, heads carried by the adjacent ends of said bars, confronting slots in said heads for receiving and sustaining therein a coin to be carried from one position to another during the ac- 130

- tuation of said bars, one of said heads being pivoted, and means operable by the actuation of one of said bars for moving said pivoted head.
5. 9. In a coin-controlled vending and change-making machine, the combination with a casing, of a magazine mounted to rotate within the casing and inclosed thereby and comprising a connected series of spaced 70
- 10 apart merchandise-holding stacks, a set of coin-holding stacks in association with each of the merchandise-holding stacks, the coin-holding stacks of each set being capable of holding coins of different denominations 75
- 15 and each of the merchandise-holding stacks with its accompanying set of coin-holding stacks jointly comprising a complete vending and change-making unit, and a plurality of controlling mechanisms, each controlled by a different denomination of coin, for effecting the discharge of merchandise and coins from a different predetermined 80 number of stacks of each unit.
10. In a coin-controlled vending and 85
- 25 change-making machine, the combination with a casing, of a magazine arranged within the casing for rotary movement and comprising a top member, a bottom member, article holding stacks connecting the top and 90
- 20 bottom members at intervals, a plurality of coin holding stacks associated with each article holding stack, a pair of reciprocating coin-controlling members arranged over the top member and capable of receiving and 95
- 25 sustaining a coin between them for establishing a connection whereby to actuate the second member from the first, a pusher device having support upon the casing for ejecting articles from the article holding 100
- 30 stacks and change from the coin holding stacks, and operative connections between the second coin-controlling member and said 105
- 35 pusher device.
11. The combination with a magazine having a plurality of groups of stacks, an independently operated ejector device for each 110
- 40 stack of each group, a plurality of master-pushers, and contact members fixed to the master-pushers and adapted each to engage 115
- 45 and simultaneously operate a different predetermined number of ejectors of each group.
12. The combination with a rotary magazine having a plurality of groups of stacks, 120
- 50 of stepping mechanism therefor, an ejector device associated with each stack of each group, a plurality of master-pushers, and contact members fixed to the master-pushers and adapted each to engage and simultaneously operate a different predetermined 125
- 55 number of ejectors of each group of stacks.
13. In a vending and change-making machine, the combination with a pair of coin chutes representing a deposit chute and a 130
- 60 delivery chute arranged with their adjacent ends out of alignment, of a pair of reciprocating members having means for returning them to normal position when thrust, said members being cooperatively headed to receive and sustain a coin from the deposit 70
- 65 chute for establishing a connection whereby to actuate one member from the other, one of the heads being pivoted, and means for tripping said pivoted head to swing the sustained coin into the delivery chute during 75
- 70 the thrusting action of said members.
14. In a combined vending and change-making machine, the combination with a rotary magazine having a plurality of groups of stacks including merchandise-stacks and 80
- 75 coin-stacks, of stepping mechanism therefor, an ejector device associated with each of the merchandise-stacks and coin-stacks, a master-pusher for actuating the ejector devices and located in relation to the magazine so 85
- 80 that said groups of stacks may be brought successively therebefore under the operation of the stepping mechanism, means for operating the master-pusher comprising a pair of reciprocating members arranged in 85
- 85 spaced end to end relation and formed to sustain a coin between them by which to operate the second member from the first, and an operative connection between the 90
- 90 second member and the master-pusher.
15. In a coin-controlled vending and 95
- 95 change-making machine, the combination of a pair of reciprocating coin-controlling members co-operatively headed to receive a coin between them for establishing a connection whereby to actuate the second member from the first, one of the heads being pivoted to swing out of cooperative relation 100
- 100 to permit the discharge of the sustained coin, and means for swinging said head at a predetermined place during the movement of its member.
16. In a coin-controlled vending and 105
- 105 change-making machine, the combination of a pair of reciprocating coin-controlling members co-operatively headed to receive a coin between them for establishing a connection whereby to actuate the second member from the first, one of said heads being pivoted to swing out of co-operative relation 110
- 110 to permit the discharge of the sustained coin, means for swinging said head at a predetermined place during the movement of its member, a pivoted kick-out bar, and 115
- 115 means forming a connection between one of the members and said kick-out bar for causing the latter to impinge the coin during the swinging of said head.
17. In a coin-controlled vending and 120
- 120 change-making machine, a pair of reciprocating coin-controlling members co-operatively headed to receive a coin between them for establishing a connection whereby to actuate the second member from the first, one of said heads being pivoted to swing out of 125
- 125

co-operative relation to permit the discharge of the sustained coin, means for swinging said head at a predetermined place during the movement of its member, in combination 5 with a magazine having merchandise-stacks and coin-stacks, ejector devices associated with said stacks and adapted to discharge merchandise and coins therefrom, and means including a master-pusher under the control 10 of said second coin controlling member for actuating the ejector devices.

18. In a coin-controlled vending and change-making machine, a pair of spaced apart coin-controlling members which tend 15 to return to normal position when thrust, vertically extending heads with co-operative grooves on the confronting ends of said members, the head on the second member being pivoted, a spring normally maintaining 20 said pivoted head in co-operative relation with the first head, to sustain a coin between them for establishing a connection between the members whereby the second member will be thrust from the thrusting movement 25 of the first, and a trip located in the path of the pivoted head to swing the latter on its pivot for the discharge of the coin during the movement of the second member.

19. In a coin-controlled vending and 30 change-making machine, the combination with stationary frame elements, of a pair of spaced apart coin-controlling members slideable therein and means tending to return them to normal position when thrust, vertically 35 extending heads with co-operative grooves on the confronting ends of said members, the head on the second member being pivoted, a spring normally maintaining said pivoted head in co-operative relation with the first head, to sustain a coin between them for establishing a connection between the members whereby the second member will be thrust from the thrusting movement of the first, a trip projecting from a frame element 40 to come in the path of the pivoted head to swing the latter on its pivot for the discharge of the coin during the movement of said second member, and a kick-out bar pivoted to a frame element and operated by one 45 of said members for impinging said coin and positively discharging it during the swinging of said pivoted head.

20. In a coin-controlled vending and change-making machine, a plurality of coin-

controlling mechanisms adapted to be actuated, a master-pusher under the control of each coin-controlling mechanism, a magazine rotatable about said master-pushers and constructed with a plurality of stacks arranged in groups in circular order, a structurally independent ejector device associated with each stack, and a contact member fixed to each master-pusher, said contact members being differentiated and adapted each to engage and operate a different number of the 65 ejector devices of the stack groups.

21. In a coin-controlled vending and change-making machine, a pair of spaced apart coin-controlling members which tend to return to normal position when thrust, 70 vertical heads with co-operative grooves on the confronting ends of said members and extending downwardly a distance from the center line of thrust, the head on the second member being pivoted, a spring normally 75 maintaining said pivoted head in co-operative relation with the first head, said heads being adapted to sustain two coins between them, one upon the periphery of the other, the upper coin establishing a connection between the members whereby the second member will be thrust from the thrusting movement of the first member, and a trip located 80 in the path of the pivoted head to swing the latter on its pivot for the discharge of the 85 coins during the thrusting movements of the members.

22. In a coin-controlled vending and change-making machine, a pair of spaced apart coin-controlling members which tend 90 to return to normal position when thrust, vertical heads with co-operative grooves on the confronting ends of said members and extending downwardly a distance from the center line of thrust, the head on the second 95 member being pivoted, a spring normally maintaining said pivoted head in co-operative relation with the first head, said heads being adapted to sustain a coin between them below the center line of thrust for establishing a connection whereby said pivoted head 100 will be swung on its pivot for the discharge of the coin during the thrusting movement of the first member.

In testimony whereof, I have signed my 105 name to this specification.

CLIFTON W. NIXON.
